UNITED STATES PATENT OFFICE.

JAMES B. TATEM, OF PUTNAM, CONNECTICUT, ASSIGNOR OF ONE-HALF TO THE AMERICAN TUBE & STAMPING COMPANY, OF BRIDGEPORT, CONNECTICUT, A CORPORATION OF CONNECTICUT.

PICKER STICK.

Application filed June 19, 1924. Serial No. 720,957.

To all whom it may concern:

Be it known that I, JAMES B. TATEM, a citizen of the United States, and a resident of Putnam, county of Windham, State of Connecticut, have invented certain new and useful Improvements in Picker Sticks, of which the following is a specification.

It has been the common practice to employ a picker stick constructed entirely of wood and, while this construction is of advantage in that it provides for a certain amount of desired resiliency and is a protection against serious damage to the loom in that the picker stick, being of wood, may break in the event that certain things should go wrong, thus avoiding more serious injury to other parts, all-wooden picker sticks are objectionable in that they crack and break under the normal strains to which they are subjected and, when they become broken or unserviceable, it is necessary to replace the entire stick, although it may be broken or cracked at but one end.

The aim of the present invention is to provide an improved construction of picker stick having a metallic section and a wooden section, the arrangement being such that, in the event the wooden section should break or become unserviceable, it may be readily detached from the metal section and a new wooden section substituted in its place.

The wooden section of my improved stick is relatively shorter than an all-wooden stick and may, therefore, be replaced at a lesser cost than would be the case if the stick were made entirely of wood, and thus a material saving is had.

An object of the invention is to provide a picker stick of the character described having various features of novelty and advantage and which is particularly characterized by its simplicity in construction, its economy in manufacture, its effectiveness in operation, and the ease and facility with which the sections may be dissembled and assembled.

A further aim of the invention is to provide means for taking up play between the wooden and metal sections as, for example, where the wooden section shrinks in size.

Other objects will be in part obvious and in part pointed out more in detail herein-after.

The invention accordingly consists in the

features of construction, combination of elements and arrangement of parts which will be exemplified in the construction herein-after set forth, and the scope of the application of which will be indicated in the appended claims.

In the accompanying drawing wherein I have shown, for illustrative purposes, one embodiment which the present invention may take, it being understood that this disclosure is by way of exemplification only and is not to be taken as restrictive of my invention, my improved stick being susceptible of various modifications and changes:

Figure 1 is a side view of the stick;

Fig. 2 is a detail view on a larger scale showing the connection between the sections with parts in section;

Fig. 3 is a transverse section taken on line 3—3 of Fig. 1;

Fig. 4 is a section taken on line 4—4 of Fig. 1;

Fig. 5 is a view showing the lower end of the blank of metal from which the metal section of the stick is formed; and

Fig. 6 is a view showing, on a reduced scale, another embodiment.

Referring to the drawing in detail, 10 designates the metal section, and 11, the wooden section. In the present illustrative disclosure, the metal section is shown as being channel shape in cross section, but it is to be understood that, while this is the preferred form so far as certain features of the invention are concerned, the metal section may have a shape other than that illustrated. 15 Preferably, the metal section is formed from sheet metal by cutting out a blank to the desired configuration, and then bending or pressing it to final shape. In the present instance, the lower end of the blank, as will be seen most clearly from Fig. 5, has one corner rounded and its other corner cut away, as at 12, and then the blank is bent along the dotted lines of Fig. 5 so as to form the flanges, the outer flange being curved at 20 its lower end, as at 13, and the edges of the notch or cut away portion 12 being in engagement, as shown in Fig. 1. The strap 14, shown in dotted lines Fig. 1, and to

which strap a spring is adapted to be connected, engages against the rounded portion 13. 25

For the purpose of maintaining the flanges

of the metal section in proper relation and to furnish a substantial bearing for the stud or bolt on which the picker stick is mounted or pivoted, there is provided, adjacent the 5 lower end of the metal section, a wooden insert or block 15 having a through opening 16. The flanges of the metal section are provided with openings in alignment with the opening 16 of the block and, preferably, the edges of the openings in the flanges are flanged inwardly so as to form bosses 17 which constitute substantial bearings for the bolt or stud. Since the bolt or stud has a long bearing in both the block and the 10 bosses, there is but little or no wear between the parts, a feature of considerable advantage. From Fig. 1, it will be seen that the sides of the block 15 are channelled or grooved, as at 18, so as to accommodate the 15 bosses. The bosses thus center the block and hold it in proper position.

The lower end of the wooden section of the picker stick fits between the flanges of the metal section and is secured in position in suitable manner as, for instance, by means 20 of bolts 20 passing through the flanges and the wooden section. Preferably, there is provided between the metal section and the wooden section a wedge 21, the purpose of 25 which is to take up play or looseness between the sections as, for instance, when the wooden section shrinks, and this wedge is further of advantage in that it may be employed for adjusting the height of the lug 30 or sweep-stick strap 22. In the present instance, the wedge 21 is interposed between one of the flanges of the metal section and the opposed face of the wooden section and is slotted, as at 23, so as to accommodate the 35 bolts 20. That face of the wedge which engages the wooden section is provided with teeth 24 which bite into the wood and thus hold the wedge in adjusted position and 40 against vertical creeping. Preferably, the lug strap 22 is connected to the wedge so that the strap may be adjusted by varying the position of the wedge, and also to cause the wedge to be normally held and urged into tighter wedging position by the pull 45 on the lug strap. To this end, in Figs. 1, 2 and 3, the wedge is provided with an arm 26 which extends downwardly alongside of the metal section, and the lug strap 22 is connected to the lower end of this arm in any suitable manner, as by means of a loop 50 or hanger strap 27. In Fig. 6, the lug strap holder is separate from the wedge. It has a resilient arm 26' carried by an attaching portion 30 secured on the outside of the metal section by the bolts 20. The attaching portion is slotted, as at 31, to permit the holder to be adjusted longitudinally of the picker stick when it is desired to change the 55 position of the lug strap.

60 It will be seen from the foregoing de-

scription, taken in connection with the drawings, that my improved picker stick is very simple in construction and may be economically manufactured. The wooden section is clamped in place in such manner that it may be readily removed. The metallic section may be easily and cheaply formed and is strong and durable. The wooden section is secured in place in a simple manner, permitting it to be substituted by a new one when the old one has become broken or worn out. In the embodiment of Figs. 1, 2 and 3, the position of the lug strap may be changed by loosening the nuts on the bolts 20, adjusting the wedge, and then turning up the 65 nuts to clamp the wedge in position. It will be noted that the strains exerted on the lug strap tend to urge or pull the wedge downwardly so that play between the metal and wooden sections is automatically taken up. 70 The wedge cannot move upwardly on account of the teeth 24 which, preferably, are in the form of saw teeth. The arm 26 provides the picker stick with a certain amount of resiliency which makes it more effective 75 in operation.

80 As many changes could be made in the above construction and many apparently widely different embodiments of this invention could be made without departing from 85 the scope thereof, it is intended that all matter contained in the above description or shown in the accompanying drawing shall be interpreted as illustrative and not in a 90 limiting sense.

95 It is also to be understood that the language used in the following claims is intended to cover all of the generic and specific features of the invention herein described and all statements of the scope of the 100 invention which, as a matter of language, might be said to fall therebetween.

105 I claim as my invention:

1. A picker stick having a metal section and a wooden section with its lower end 110 fitting in the upper end of said metal section, a wedge between the metal and wooden sections, and means for securing the parts together.

115 2. A picker stick having a metal section and a wooden section with its lower end fitting in the upper end of the metal section, a wedge between the side of the wooden section and the metal section provided with 120 teeth adapted to bite into the wooden section, and bolts passing through said sections and said wedge for securing the parts together.

125 3. A picker stick having a metal section and a wooden section with its lower end fitting in the upper end of the metal section, a wedge between the metal and wooden sections and having teeth engaging the wooden section shaped to permit the wedge to creep into closer wedging position and to prevent 130

the wedge from creeping out of wedging position, and means for securing the parts together.

4. A picker stick having a metal section and a wooden section with one end removably mounted in the adjacent end of the metal section, a member between said sections for taking up play and looseness therebetween, and a lug strap connected to said member and normally urging the same into operative position.

5. A picker stick having a metal section and a wooden section with its lower end fitting within the upper end of the metal section, a wedge between the sections, a lug strap connected to the wedge, and means for removably securing the sections together.

6. A picker stick having a metal section and a wooden section with its lower end fitting within the upper end of the metal section, a wedge between the sections provided with teeth engaging the wooden section and arranged to permit the wedge to creep into closer wedging position and to hold it against creeping out of wedging position, means for clamping the sections together, and a lug strap connected to the wedge and adapted to urge the same into closer wedging position.

7. A picker stick having a metal section and a wooden section with its lower end fitting within the upper end of the metal section, a wedge between the sections having an arm extending downwardly alongside of the metal section, and a lug strap connected to said arm.

8. A picker stick having a metal section channel shaped in cross section, and a wooden section with its lower end fitting in the upper end of the metal section, said metal section having, in its opposed walls, openings with the edges thereof flanged inwardly to provide bosses, and a filler block between said flanges and having a hole in registry with the openings of the bosses and forming therewith a bearing for a stud or pivot, said filler block being grooved on its side faces to accommodate said bosses.

9. A picker stick having a metal section and a wooden section removably secured in the upper end of the metal section, said metal section being channel shaped in cross section and having one of its side flanges curved across the bottom of the metal section to provide a curved strap engaging surface.

JAMES B. TATEM.
